UNITED STATES PATENT OFFICE

JOHN HAYS HAMMOND, JR., OF GLOUCESTER, MASSACHUSETTS

PIANO WITH TONE MODULATORS

Application filed December 11, 1928. Serial No. 325,282.

This invention relates to musical instruments of the percussive type, and more particularly, to a new and improved electrically operated mechanism for controlling the tone 5 thereof.

The quality of the music produced by a musical instrument such as a piano can be very greatly enhanced by providing a sound insulated casing for the instrument with controllable apertures therein for regulating the volume of sound emitted from the instrument. Furthermore, an instrument so equipped can be made to produce a variety of novel effects, and can be employed to advantage in combination with symphonic orchestras. I have discovered that when a plurality of closures are arranged in different positions with respect to the sounding board and the strings, the sound emitted through the respective apertures differs in quality and timbre, and I have found that when the apertures and the closures therefor are arranged to be opened successively the control of the tone dynamics is greatly improved, and the attractiveness of the music is very greatly increased. Broadly stated, the present invention relates to an improved musical instrument for producing these novel effects.

An object of the present invention is to provide a simplified control for varying the tone of the musical instrument.

Another object is to provide electrical means for controlling the tone of a piano provided with variable shutters.

A further object is to provide, in a piano having a plurality of variable reflectors, electrical means for successively operating said reflectors.

The above objects and others which will be apparent as the nature of the invention is disclosed, are accomplished by providing a solenoid in operative relationship to each of the several reflectors and successively controlling the operation of the solenoids by a multiple contact switch which is operated by a foot pedal of the piano. The reflectors are preferably divided into two groups at the upper and lower portions respectively of the piano and are so arranged that the various 45 units of the top group are successively closed

before the units of the lower group have operated.

The invention also consists in certain new and original features of construction and combinations of parts hereinafter set forth 55 and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a 60 part thereof, in which

Fig. 1 is a top plan view of a piano constructed in accordance with the present invention;

Fig. 2 is a side elevation thereof;

Fig. 3 is a schematic diagram showing the solenoids and the electrical control circuits; and

Fig. 4 is a fragmentary front elevation partly in section, showing the arrangement 75 of the electrical circuits together with the pedal control mechanism.

Like reference characters denote like parts in the several figures of the drawings.

In the following description and in the 80 claims parts will be identified by specific names for convenience, but they are intended to be as generic in their application to similar parts as the art will permit.

In the form of the invention shown in the 85 accompanying figures, the system is applied to a grand piano 10 which is provided with the usual strings 11 mounted in a frame 12 (Fig. 4). The strings 11 and the frame 12 are located above the sounding board 13 which divides the interior of the piano into two sound chambers 14 and 15, the former located above and the latter located below said sounding board. The piano is also provided with the usual piano action 16 which is operated by 90 means of a set of keys 17 in a well known manner.

The casing of the piano 10 is constructed of laminated sections 18 and 19 between which is a layer of sound absorbing material 21 100

which tends to prevent the escape of the sound from the interior of the piano.

On the under side of the piano 10 is secured a block 22 from which are suspended two uprights 23 and 24 which carry at their lower end a pedal block 25. Mounted in the block are three pedals 26, 27 and 28, the last two controlling the sustainuto and loud pedal action of the piano respectively.

10 The pedal 26 is connected to a rod 29, the upper end of which engages one arm of a bell crank 31 which is pivoted for rotation in a bracket 32. The other arm of the bell crank 31 is slidably secured in cylindrical member 33 which is rotatably mounted on a rod 34 of insulating material, carrying a conducting strip 38, and is held in place by means of a plate 35 which is secured to said rod. The rod 34 is slidably mounted in two 15 brackets 41 and 42 which are secured to the under-side of the piano 10 and is held in the position shown by means of a spring 36 which is secured to a bracket 37 attached to the block 22. Said brackets 41 and 42 carry a 20 bar of insulating material 43 upon which are mounted 17 contacts 44 to 60. The contacts 44 to 59 are connected to 16 conductors 64 to 79 which go to the windings of 16 solenoids 84 to 99. The other sides of the 25 windings of these solenoids are connected by a plurality of conductors to a common return conductor 101 which is connected to one side of a battery 102, the other side of which is connected by a conductor 103 to the contact 30 35 60.

Each solenoid is mounted in a frame 104 which is rotatably mounted on a pivot 105 which is carried by the frame of the piano 10. Said solenoids are provided with cores 106 to which are rigidly secured collars 107 between which and the solenoids are mounted springs 108. The cores 106 of the solenoids pass through screw eyes 109 which are secured to a plurality of pivoted reflectors 45 114 to 129.

Reflectors 114 to 121 are pivotally mounted for rotation about their longitudinal axes in the lower part of the framework of the piano and the reflectors 122 to 129 are mounted for 50 rotation about their longitudinal axes in the upper part of the framework of the piano. At the front and rear ends of the lower set of reflectors are mounted two plates 131 and 132 which serve to close the lower portion of 55 the piano below the sounding board so that when the lower set of reflectors is closed there will be formed a sound chamber below the sounding board. At the front and rear ends of the upper set of reflectors are mounted 60 two plates 133 to 134 which serve to close the upper portion of the piano above the sounding board so that when the upper set of reflectors is closed there will be formed a sound chamber above the sounding board containing 65 the strings of the piano.

In the operation of the form of the invention just described, when the pedal 26 is depressed, the rod 29 will be elevated thereby rotating the bell crank 31 in a counter clockwise direction, thus moving the rod 34 to the left. This motion causes the conducting strip 38 to successively engage the contacts 60 to 70 44, thus successively energizing the solenoids 99 to 84. As each solenoid is energized, it causes its core to be moved inwardly against the action of the spring 108 thus causing the corresponding reflector to be closed. In this way as the pedal 26 is depressed, the reflectors will be successively closed starting with the one at the top in the rear of the piano and 75 closing the top set successively after which the bottom set is closed successively starting with the one at the rear until the reflectors are entirely closed.

When the pedal 26 is released the spring 36 will tend to move the rod 34 to the right, thus successively breaking contact between the strip 38 and the contacts 44 to 60. This causes the solenoids 84 to 99 to be deenergized 80 successively and after each solenoid is deenergized the corresponding spring 108 will cause the core to move outwardly, thereby opening the corresponding reflector. In this way, as the pressure on the pedal 26 is decreased, the reflectors will be successively 95 opened starting with the lower front and finishing with the upper rear.

By suitably controlling the pedal 26 the musician may modify the sound and cause delicate variations of the sound intensity 100 transmitted from any desired part of the instrument, and thus impart agreeable variations in quality to the music. By carefully adjusting and controlling the pedal, the qualities of directly transmitted sound, or of reflected sound, may be imparted in desired 105 proportions.

While certain novel features of the invention have been shown and described and are pointed out in the annexed claims, it will be 110 understood that various omissions, substitutions and changes in the forms and details of the device illustrated and in its operation may be made by those skilled in the art without departing from the spirit of the invention. 115

What is claimed is:

1. A modulating system for a musical instrument comprising a tone modulating control device, a plurality of tone reflectors arranged on different sides of said instrument for variably controlling the volume of sound emitted from the instrument in different directions, electrical means for independently operating said reflectors and means for successively operating said electrical means for closing or opening said reflectors. 120 125

2. A modulating system for a percussive musical instrument, comprising a plurality of tone reflectors arranged on different sides 130

of said instrument for variably controlling the volume of sound emitted from the instrument in different directions, and electrical means including a system of electro-magnetic elements for successively operating said reflectors.

3. A modulating system for a musical instrument comprising a plurality of tone reflectors arranged in groups, electromagnetic means for operating each of said tone reflectors independently, control circuits for said electromagnetic means, and means for successively energizing said circuits for closing said reflectors and successively deenergizing said circuits for opening said reflectors.

4. A modulating system for a musical instrument comprising a plurality of tone reflectors arranged in groups, electromagnetic means for independently operating said reflectors, and a control means for successively operating each of said electromagnetic means whereby said groups of tone reflectors are operated in sequence.

5. A musical instrument having a vibratory sound producing element, a substantially sound proof casing having controllable apertures arranged on different sides of said instrument for controlling the emission of sound from said element in different directions, a plurality of tone reflectors for variably closing said apertures, means for normally maintaining said reflectors in open position, electromagnetic means associated with each of said reflectors, control circuits therefor, a contact associated with each circuit and a switch for successively opening or closing said contacts.

6. A modulating system for a musical instrument comprising a plurality of resonating chambers, a plurality of sound wave reflectors for variably and independently controlling the volume of sound emitted from different resonating chambers, a tone modulating pedal, an electrical controller operated thereby, electromagnetic devices associated with said reflectors and circuits interconnecting said controller and said electromagnetic devices whereby said reflectors may be controlled by the position of said pedal.

7. In a percussive instrument having vibrating strings, resonating chambers above and below said strings, a plurality of variable reflectors forming a closure for said chambers, means for successively opening said reflectors beginning with the reflectors at one end of one of said chambers and ending with the reflectors at the opposite end of the other of said chambers, and means for successively closing said reflectors in opposite sequence.

8. In a grand piano, a casing forming sound chambers above and below the sounding board thereof, reflectors mounted in the top and bottom of said casing for variably

closing said chambers, means for successively operating said reflectors beginning at a reflector at one end of the lower group and ending at a reflector at the opposite end of the other group, and means for successively closing said reflectors in opposite sequence.

9. In a piano, a casing forming sound chambers on opposite sides of the sounding board, groups of reflectors forming closures for each of said chambers, means for operating said groups in sequence whereby the reflectors of one of said groups are opened prior to the operation of the other of said groups, and means for closing said reflectors in opposite sequence.

In testimony whereof I have hereunto set my hand.
